HORN

David G. Blattner, Mountain Lakes, N. J., assignor to Bell Telephone Laboratories, Incorporated, New York, N. Y., a corporation of New York

Application April 7, 1933, Serial No. 664,891

14 Claims. (CL. 181—27)

This invention relates to horns and more particularly to horns suitable for the transmission of speech and music such as are used with phonograph reproducers and loudspeakers.

5 One object of the invention is to provide a horn which will give a uniform distribution of the sound energy at all frequencies over a large area.

Another object is to increase the efficiency of 10 the horn as a sound radiator at low frequencies.

It is well known that in conventional loudspeaker horns the sound waves of low frequencies are radiated from all parts of the mouth of the horn but that as the frequency is increased

15 the waves become more and more concentrated so that the highest frequencies are projected as a narrow beam with the result that the quality of complex sound, such as music, varies greatly with the position of the

20 listener in the sound field. A much more uniform distribution of the sound energy at all frequencies is obtained according to this invention by arranging in the mouth of the horn vertical, diverging partitions extending back into the

25 horn far enough to intercept effectively the waves of both high and low frequencies. In this way the high frequency waves are conducted to the various portions of the horn mouth and projected along with the low frequencies

30 more uniformly over the desired area. Preferably, the total cross-sectional area of the horn increases logarithmically at the same rate throughout its length.

It is also well known that if a horn is to be 35 efficient for low frequencies down to its cut-off, the horn mouth dimensions should be large in comparison with the wave length of the cut-off frequency. For the efficient radiation of the very low frequencies required in reproducing high quality music this means that the horn mouth should be very large. In commercial designs, in order to limit costs and space requirements to reasonable proportions, it is common practice to limit the mouth opening to less than 40 the optimum dimensions.

Applicant has found that, for low frequencies, two identical, conventional loudspeakers connected in parallel to a source of power will produce more sound than one of the speakers operating alone and drawing the same electrical power as the two operating in parallel. In accordance therefore with an important feature of the invention the subdivided passages comprising the horn mouth are separated from each other by partition walls of a thickness some-

what comparable to the dimensions of the passages. In this way the radiation resistance of the horn mouth and hence its low frequency efficiency will be made greater than that of a single mouth opening having the same area as the combined area of the openings in the divided horn, without excessively increasing the horn dimensions.

5 A horn made in accordance with this invention has a sound field practically uniform in a commercial sense covering a spread of 90° as compared with 30° for a similar horn of single mouth opening having a sound passage of the same dimensions and taper.

In the drawings:

10 Fig. 1 shows one form of folded exponential horn having its bell portions successively subdivided to reduce the directional effect;

Fig. 2 is an elevation, partly in section along the line 2—2 of Fig. 4, of a common commercial 20 horn showing a relatively inexpensive arrangement of partitions for approximating the energy distribution obtained in the horn of Fig. 1;

Fig. 3 is a view looking into the mouth of the horn of Fig. 2 showing the fixed partition walls 25 for improving the low frequency response; and

Fig. 4 is a sectional view along the line 4—4 of Fig. 2 showing the arrangement of the tapered partition walls.

30 The more uniform distribution of the high frequency waves according to this invention, will be more clearly understood by considering first the fundamental requirements of such distribution and then the manner in which these requirements are met in a practical structure. 35

If it were possible to provide a spherical source of sound, that is, a source consisting of a sphere the surface of which has a radial vibratory motion in phase at every point of the surface at all frequencies, sound would be radiated uniformly outward in all directions from the center of the sphere. If further the vibrating surface of the sphere is traversed by the walls of a pyramid having its vertex at the center of the sphere the sound distribution will not be affected there- 45 by. Throughout the space included within the pyramid the sound distribution will not be changed if that part of the spherical source not intercepted by the pyramid is removed. Furthermore, the sound distribution within this 50 space will be altered only slightly if the bounding walls of the pyramid are removed provided the superficial dimensions of the spherical segments within the pyramid are large compared with the wave length of the radiated sound. 55

From this reasoning it is seen that in order to get the ideal distribution of a spherical source within a region defined by a certain solid angle, it is necessary and sufficient that over a spherical surface having its center of curvature at the vertex of the angle and having an area whose superficial dimensions are large compared with the wave length of sound, the radial motion of the air on this surface shall vibrate at equal 10 amplitudes and in phase.

Since in practice a horn is driven by a receiver unit in which the diaphragm sets up a plane wave in the throat of the horn the problem resolves itself into one of causing the sound 15 waves of all frequencies of interest to emerge from the mouth of the horn in phase on a spherical wave front and with a uniform distribution over a length of arc at least comparable to the longest wave length to be transmitted.

20 This condition is approximated by successively subdividing the bell portion of the horn in at least one plane so that the subdivided passages are kept small enough to prevent undue concentration of the higher frequencies in any 25 passage. If the horn mouth is contoured as in Fig. 1 so that the several paths are all of the same length, the sound waves will be projected as a series of separate waves which merge into a single wave conforming substantially to the 30 contour of the mouth opening and moving outwardly as if originating at the virtual source 10.

The expressions "horn throat" and "horn mouth" are used to designate in a general way the portions of the horns adjacent the receiver 35 unit and the mouth opening respectively but since the cross-sectional area of the horn increases at the same rate throughout its length, there is no definite dividing line between these portions. The horn of Fig. 1 is composed of two 40 sections 36 and 37 and the throat portion may be considered as consisting of the section 36 and possibly a small part of section 37. The horn of Fig. 2 is composed of three sections 38, 39 and 23 and the throat portion may be considered as 45 consisting of section 38 and possibly a part of section 36.

The central subdividing partition 11 extends backward toward the receiver unit 12 to a point where the cross-section of the horn is so small 50 that the wave front is substantially planar for all frequencies. As the horn expands the width of each subdivision becomes comparable to the wave length of the higher frequencies and another partition such as 13 is required to prevent undue concentration of these frequencies. 55 These channels are again subdivided as by walls 14 and 15 so that each of the sixteen openings at the mouth of the horn will emit a wave containing all the component frequencies of the sounds being reproduced. It will be understood, 60 of course, that the number of partitions used in any given horn will depend upon the range of frequencies to be covered and the permissible variation from the ideally uniform distribution.

In the horn shown in Figs. 2, 3 and 4 the 65 general principles discussed above have been applied to a commercial structure to approximate the desired distribution without resorting to an unduly expensive construction. The long 70 partitions 21, 22 divide the entrance to the mouth portion 23 of the horn into three substantially equal parts so that a considerable proportion of the high frequency energy is diverted into the lateral passages 24 and 25. Each 75 of these passages is again subdivided by parti-

tions such as 26 and 27 which divert a part of the high frequency energy to the passages 28 and 29. When the wave front 30 in the central passage 31 reaches the mouth of the horn the wave front in the other passages will be disposed along an arc as indicated by the dotted line and corresponding to a virtual spherical sound source 32. While from the standpoint of high frequency energy distribution it is unnecessary to continue the partitions beyond this 10 line of wave fronts, it is sometimes desirable to do so for other reasons. It is much easier to build such a horn with a planar mouth opening as shown and in this way reflection effects are minimized when the horn is located behind 15 a screen as in the usual theater installation.

The proper thickness of the partitions at the horn mouth depends on a number of factors. In general, for a given cut-off frequency, the longer the horn and the larger its mouth opening, 20 the nearer to its cut-off frequency will the radiation resistance be maintained so that it is quite possible as pointed out above to design the horn to respond satisfactorily to the desired low frequencies without relying on the partitions to 25 increase the low frequency response. When it is desirable from cost and space requirement standpoints to keep the horn as small as possible, the horn length may be less than the quarter wave length of the lowest frequencies to be 30 projected. In such cases a relatively greater low frequency correction is desirable and the thickness of the ends of the partitions should therefore be a greater proportion of the width 35 of the sound passages as viewed in Fig. 4. 35

Another important consideration is the required angle of dispersion. For since the total cross-sectional area of the passages expands logarithmically at the same rate toward the horn mouth, the thicker the partition walls 40 are made, the greater the angle of dispersion will be for a given horn taper such as shown in Fig. 2. This particular horn has an effective length of about 13 feet and a cut-off frequency of about 60 cycles. The partition walls 45 are 3 $\frac{3}{8}$ inches and the sound passages are 5 $\frac{3}{4}$ inches at the horn mouth so that the partition thickness is greater than one half the spacing between them, or, in other words, the area of the ends of the partitions is greater than one half the total mouth opening. This arrangement is found to give a considerable improvement in low frequency response from the cut-off up to about 150 cycles. Since these walls 55 are not intended as resonators, but are used merely to disperse the sound over the required angle, they should be made as rigid as possible as by upright members 33, 34 and 35 or any other suitable means.

What is claimed is:

1. In a horn, a logarithmically tapered throat portion having a single passage and a mouth portion comprising a plurality of diverging sound passages each increasing in cross-sectional area at the same rate as the throat portion. 65
2. In a horn, a throat portion of logarithmic taper having diverging side walls, a mouth portion having side walls diverging at a greater angle than the side walls of the throat portion, and rigid partitions in the horn mouth extending 70 toward the throat portion and varying in thickness so that the net effective cross-sectional area of the mouth portion increases logarithmically at the same rate as the throat portion. 75

3. A horn comprising a throat portion having a single passage, a mouth portion of rectangular cross-section and a plurality of diverging non-resonant partitions subdividing the horn so that the net effective cross-sectional area of the horn increases logarithmically at substantially the same rate throughout its length.
4. A horn comprising a throat portion, a rectangular mouth portion, and non-resonant partitions dividing the mouth portion into a plurality of diverging passages, said partitions extending from the mouth of the horn toward the throat portion to a point where the sound waves are substantially planar and increasing in thickness towards the horn mouth.
5. A horn comprising a throat portion and a mouth portion of rectangular cross-section, a plurality of vertically disposed partitions spaced in the mouth portion extending substantially longitudinally of the horn axis, and increasing in thickness towards the mouth of the horn.
6. A horn comprising a throat portion, a mouth portion of rectangular cross-section, a plurality of short and a plurality of relatively longer vertically disposed partitions, the outer ends of all terminating at the mouth of the horn, said longer partitions being interposed at intervals between the shorter partitions and symmetrically disposed with respect to the vertical medial plane of the horn mouth.
7. A horn comprising a throat portion, a mouth portion of rectangular cross-section, the horizontal dimension of the bell portion at its mouth being substantially greater than its vertical dimension and a plurality of wedge-shaped partitions extending between the top and bottom walls of the horn and having a total end area at the mouth of the horn greater than one half the area of the total mouth opening.
8. A horn comprising a throat portion, a mouth portion and a plurality of equally spaced and vertically disposed partitions in said mouth portion, said partitions tapering uniformly from their outer and thicker edges to their inner and thinner edges, the thickness of the outer edges of said partitions being greater than one half the spacing therebetween.
9. A horn comprising a throat portion, a mouth portion, a plurality of wedge-shaped par-
- titions tapering from a maximum thickness at the mouth of the horn to a thin edge at that portion of the horn where the high frequency sound beam substantially fills the horn.
10. In a horn comprising a throat portion, and a mouth portion each having the same logarithmic taper, a plurality of wedge-shaped partitions vertically disposed and dividing the horn into a plurality of sound passages having the same logarithmic taper, both the partitions and the sound passages increasing in cross-sectional area toward the mouth opening.
11. A horn comprising a throat portion, a mouth portion having plane diverging side walls and outwardly curved upper and lower walls, and wedge-shaped partitions extending between said upper and lower walls dividing said mouth portion longitudinally into a plurality of sound passages, a plurality of shorter wedge-shaped partitions dividing said passages into smaller passages, the end area of the partitions at the mouth opening being approximately one third the over-all mouth area.
12. A horn comprising a throat portion and a rectangular mouth portion having a greater horizontal dimension than vertical, and partitions dividing said mouth portion vertically into a plurality of passages, said partitions being substantially non-resonant wedge-shaped members decreasing in thickness from the mouth of the bell portion toward their inner extremities.
13. In a horn, a longitudinally tapered throat portion having a single passage and a mouth portion comprising a plurality of diverging sound passages each increasing in cross-sectional area at the same rate as the throat portion, the overall length of the horn as measured through each of said passages and said throat being substantially the same.
14. A horn comprising a throat portion having a single passage, a mouth portion of rectangular cross-section and a plurality of diverging non-resonant partitions subdividing the horn so that the net effective cross-sectional area of the horn increases logarithmically at substantially the same rate throughout its length, which measure through each subdivision is substantially the same.

DAVID G. BLATTNER.
